Design No. 579

Samuel Pierce Esq. J. J. Dulley
Assignors to Johnson, Bow, & Fuller

Book store design

Patented Oct 12, 1853

Sam'l. Pierce, and

Ms. 579

James J. Dulley of Troy, N. Y.

Assignors to

Johnson, Cox, & Fuller, of Troy, aforesaid
Letters Patent No^o 579 - Dated July 12th 1853,

The schedule referred to in these Letters Patent and making part of the same

To all whom it may concern:

Be it known that we, Samuel Pierce and J. J. Dulley, of Troy, in the County of Rensselaer, and State of New York, have invented or produced a new & original Design of Cook stove which we call the "Golden State" and we do hereby declare that the following is a full, clear and exact description of the same, reference being had to the annexed perspective drawing making a part of this specification.

The description of our stove design is as follows, viz: A, is the top plate - B, is the jamb - the upper part is formed with the architrave C, upon which is arranged the pendants (a a), upon the plinth of the base is arranged a series of oval ornaments (b b) - D, and E, are the oven doors upon the panels of which are arranged the ornaments (c, and d.) - F, is the fire door upon the panel of which is the ornament (e) - (f f) are ornaments starting on the plinth of the jamb and running up on to the pilasters (g, g) - G, is the front plate which has an architrave at the top, upon which are arranged the same kind of ornaments that are used on the jamb, H H, are the front doors, upon the panels of which are arranged the ornaments (h, h) - I, is the hearth, which has the ornamental moulding (j) forming the outside edge of the same - (K) is the moulding of the bottom plate, L is the leg with the ornament (l) upon the face of it.

Having thus described our new design of cook

File 579

2
Stove, What we claim as new, and desire to secure by Letters Patent, is the ornamental design and configuration of cook stove plates, such as herein described and represented in the annexed drawing.
